DESIGN FOR A SHIELD FOR BILLIARD TABLE POCKETS OR THE LIKE

Alfred F. Debicki, Muskegon, Mich., assignor to The Brunswick-Balke-Collender Company, Chicago, Ill., a corporation of Delaware

Application May 29, 1942, Serial No. 107,053

Term of patent 14 years

To all whom it may concern:

Be it known that I, Alfred F. Debicki, a citizen of the United States, residing in the city of Muskegon, county of Muskegon, State of Michigan,
have invented a new, original, and ornamental Design for a Shield for Billiard Table Pockets or the Like, of which the following is a specification, reference being had to the accompanying drawing, forming a part hereof.

Figure 1 is a front elevational view of a shield
for billiard table pockets or the like, showing my new design;

Figure 2 is a side elevational view thereof;
Figure 3 is a top plan view.

I claim—

The ornamental design for a shield for billiard table pockets or the like, as shown.

ALFRED F. DEBICKI.
